UNITED STATES PATENT OFFICE.

GEORGE H. EMERSON, OF BALTIMORE, MARYLAND.

METHOD OF MAKING STAY BOLTS.

Application filed February 16, 1923. Serial No. 619,338.

To all whom it may concern:

Be it known that I, GEORGE H. EMERSON, a citizen of the United States, residing at Baltimore city, in the State of Maryland, 5 have invented certain new and useful Improvements in Methods of Making Stay Bolts; and I do hereby declare the following to be a full, clear, and exact description of the invention, such as will enable others 10 skilled in the art to which it appertains to make and use the same.

My invention relates to a method of making stay bolts for boilers.

Among the objects of my invention are:— 15 To provide a stay bolt for boilers having high tensile strength and low transverse stiffness.

To provide a bolt having the above characteristics so constructed that all parts of 20 said bolt exposed in the water space of the boiler will be substantially of the same electric potential whereby electrolysis and quick deterioration of my improved bolt is prevented.

25 To provide a method of forming my improved bolt in a cheap and practical manner.

Heretofore, when the ordinary bolts have 30 been employed it has been necessary to make them of considerable cross section to provide sufficient tensile strength. When the bolts are made of sufficient cross section to provide the needful tensile strength they then had considerable transverse stiffness so 35 that as relative movements of the sheets of the boilers to which the ends of a stay bolt were secured took place a considerable strain was thrown upon the bolts which tended to loosen its fastening in the sheets or to shear 40 the bolts.

Attempts have been made to overcome this 45 defect by providing bolts of high tensile strength and small cross section with ends of enlarged cross section and formed of a different metal for securing in the boiler sheets. The defect of this construction has been that when such bolts were used in the water space of a boiler there were different 50 electric potentials between the different metals, electrolysis resulted and the bolts soon deteriorated.

Other attempts made to provide bolts having 55 high tensile strength and low transverse stiffness comprehended the use of a core having a high tensile strength and low transverse stiffness with a twisted casing around said

core having enlarged ends for securing in the boiler sheets.

The defect of this construction was that the casing of necessity was formed of fibrous 60 metal and when the centre of the casing was twisted with reference to the ends, the twisted metal had a different electric potential when placed in the water space of a boiler from the ends thereof; consequently, 65 electrolytic action took place with resulting rapid deterioration of the bolt.

By my improved method, I am enabled 70 to provide a bolt having a core of high tensile strength and low transverse stiffness and in which all parts of the exposed metal when mounted in the water space of a boiler will have substantially the same electric potential so that electrolytic action is entirely 75 avoided.

In the drawings:—

Figure 1 represents the blank of metal which is to form the casing of my improved bolt.

Fig. 2 shows the casing or strengthening 80 member with the core of high tensile strength and low transverse stiffness mounted therein.

Fig. 3 shows the manner of applying the 85 swages to the blank casing in order to close same in upon the shank of the core.

Fig. 4 shows the completed stay bolt as mounted in the boiler.

In the drawings:—

5 represents the blank for the casing 90 which is bored out as at 6. After said casing is bored the core or strengthening member 7 is introduced within said hole.

The core 7 is provided at the ends with 95 balls 8—8 formed integrally with a shank 9 of a less diameter than the diameter of said balls. The core 7 is preferably constructed of material having a high tensile strength and the shank 9 is made small in diameter so as to reduce the transverse stiffness thereof. The core 7 may be made of any of the 100 alloy steels or other materials and may be treated by heat or otherwise in order to increase the tensile strength thereof.

After the core 7 is introduced in the hole 105 6, as just described, the blank 5 and core 7 are heated together and swages 10—10 applied to said blank between the balls 8—8, thus closing the walls of the hole 6 in upon the shank 9 as shown in Fig. 4.

110 After the blank 5 for the casing has been swaged, as just described, it can be threaded

on the ends at the proper locations for attachment to the boiler plates 11-11.

It is to be noted that the shank 9 is to be of such a length that the balls 8-8 will be sufficiently distant from the facing ends of the threaded portions to provide adequate strength as shown in Fig. 1.

After the threading operation has been completed, the casing is to be reduced in diameter, as shown in Fig. 1, in order to reduce the transverse stiffness of the casing.

Thus it will be seen that I provide a bolt in which but a single metal is exposed to the water in the water space of a boiler and that the fibres of said metal are not twisted and are subjected during the construction of my improved bolt to a minimum of deformation.

While I have shown balls at the end of the shank 9, it is to be understood that these shapes may be varied.

It is also to be understood that changes may be made in my improved bolt and in the method for forming the same without departing from the spirit of my invention.

I claim:—

1. The herein described method of forming bolts having high tensile strength and low transverse stiffness which consists in drilling a hole partly through a blank of metal, then introducing within said hole a strengthening member comprising a shank and enlargements on the end of said shank larger in cross section than the cross section of said shank, and then swaging said blank

between said enlargements until the walls of said hole are compressed against said shank.

2. The herein described method of forming bolts having high tensile strength and low transverse stiffness which consists in drilling a hole partly through a blank of metal, then introducing within said hole a strengthening member comprising a shank and enlargements on the end of said shank larger in cross section than the cross section of said shank, then swaging said blank between said enlargements until the walls of said hole are compressed against said shank and then turning said blank between said enlargements to a diameter smaller than the ends of said blank.

3. The herein described method of forming bolts having high tensile strength and low transverse stiffness which consists in drilling a hole partly through a blank of metal, then introducing within said hole a strengthening member comprising a shank and enlargements on the end of said shank larger in cross section than the cross section of said shank, then swaging said blank between said enlargements until the walls of said hole are compressed against said shank, then turning said blank between said enlargements to a diameter smaller than the ends of said blank, and then threading said ends.

In testimony whereof I affix my signature.

GEORGE H. EMERSON.
